CLAIM

The ornamental design for a support for paving stones or the like as shown and described.

DESCRIPTION

1.1 : Perspective view

1.2 : End elevation view

1.3 : Perspective view

The broken lines in Reproductions 1.1-1.3 represent portions of the support for paving stones or the like and form no part of the claimed design. The other broken lines in Reproduction 1.3 represent environmental subject matter and form no part of the claimed design. The curved dashed lines represent a claim boundary and form no part of the claimed design.
